UNITED STATES PATENT OFFICE.

MAURICE VITRAC, OF PARIS, FRANCE.

MARK-BUOY FOR SEAWAYS.

1,376,055.

Specification of Letters Patent. Patented Apr. 26, 1921.

Application filed August 13, 1919. Serial No. 317,300.

To all whom it may concern:

Be it known that I, MAURICE VITRAC, a citizen of the Republic of France, and resident of Paris, in the Republic of France, 5 have invented certain new and useful Improvements in and Relating to Mark-Buoys for Seaways, of which the following is a specification.

This invention relates to improvements 10 in mark buoys of that type, in which the buoy is attached to the deck of the vessel and is adapted to rise to the surface in case of wreck and sinking, to indicate the position of the vessel.

15 It is at present very difficult to exactly mark the spot where a foundered vessel lies on the bottom, even after a very short time. This difficulty arises from various causes such as ignorance of the place where the accident happened, and drift of the vessel during and especially after the accident, beneath the water and even on the bottom, in consequence of currents which act on the 20 wreck.

25 When the vessel lies at less than 180 ft. deep, it is possible to save the whole or a portion of the cargo and even to refloat the hull, but in order to do this it is necessary to locate clearly the position of the boat 30 and if possible the bow and stern.

The arrangement of a mark buoy, which forms the object of this invention, affords this facility and gives, together with the position of the ends of the boat an indication 35 as to the depth of its immersion.

It has the further advantage of requiring no manipulation at the moment of the accident, its working being automatic, and of being reasonable in price.

40 According to this invention the mark buoy is provided with a mast mounted on a cross bar and carrying at its longer end a flag and at its shorter end a dead weight which automatically raises the mast as soon 45 as the buoy is detached from the deck of the vessel.

The invention is more particularly described with reference to the accompanying drawings in which:—

50 Figure 1 is a plan view.

Fig. 2 is a section on the line *a*—*b* of Fig. 3.

Figs. 3 and 4 are sections on *x*—*y* and *c*—*d* respectively of Fig. 1.

Fig. 5 is a view of the apparatus when 55 in use.

Fig. 6 is a plan view of a modification of the apparatus.

Fig. 7 is a side elevation of the modification.

Fig. 8 is a view of the apparatus when in use.

The float is formed of two rectangular boxes or cases 1 of light wood, such as poplar or the like, closed at three of their longer 65 sides and filled with cork fastened together.

On their shorter sides these boxes are connected by two planks 2 of the same light wood, leaving between them a certain interval and forming a rigid whole.

On the top two oak planks 3 are fixed (nailed, screwed, etc.) which do not fit close together but leave between them the necessary interval 4 for the movement of a mast 5 having a flag or signal 9 which completes 75 the apparatus. The mast 5 is formed of a hollow iron tube mounted on a cross bar with a shaft 6 engaged in two trunnions mounted, one in the long inner side of one

of the floats 1, the other in a plank 15 which 80 separates the space comprised between the two floats, connecting the planks 2 into two compartments 16 and 17. The shorter end of the mast 5 carries a plummet 12 which has a suitably flattened form so as to move 85 freely in the apparatus and also to insure the raising of the mast when the buoy is detached from the ship.

The mast and its bearing and the balancing weight are, therefore, contained in the 90 compartment 16.

In the compartment 17 a rope 14 having spaced graduations is disposed of which one end 13 is attached to the float and the other 13¹ to the deck of the vessel.

95 There is no risk of failure in the working of the apparatus through the entangling of the line as whether the buoy falls into the water in one direction or the other, the mast will always be erected with its flag in the 100 air and the weight below as shown in Fig. 5.

The buoys are, when not in action, simply placed on the deck at suitable points, one at the bow, the other at the stern; each one has a mark bow or stern and is connected as stated with the deck by a 120 to 180 ft. cable 14 having graduated indications.

In case of wreck when the hull is submerged, the buoys float and immediately the weight 12 raises the masts 5 stretching the cable 14 the flags 9 rendering these arrangements visible at a long distance.

As the vessel sinks and, until it comes to rest, the attachment cable unwinds, the buoy is drawn along and finally the two buoys float signaled by their flags and the latter are maintained vertical by the weight of the plummet 12.

The cable will be of sufficient strength to resist for a considerable time. It can be replaced by a stronger.

15 It is possible to utilize ring buoys of the ordinary type as floats instead of the cases or boxes hereinbefore described. Figs. 6, 7 and 8 show this modification with the hawser carrying the plummet.

20 To the ring 21 planks 3 are attached in any suitable way, for example by cords 22, which form the deck, leaving between them the necessary interval for the movement of the mast 5.

25 On these planks the hinge 7 of the pivot 6 of the mast 5 is mounted, and for this purpose the latter has an eyelet nearer one end.

At the nearest end to this eyelet there is, on the inner face of the mast another projecting eyelet 20 which serves for the attachment of the hawser 14 which is con-

nected to an eye on a plummet 12. The plummet 12 is connected at 13 to the buoy by the cable 24. When in use the flag is maintained in a raised position by the tension of the cable 14 and the weight of plummet 12.

I declare that what I claim is:—

1. A mark buoy comprising in combination a ring float, two planks on one side of said float, means to connect said planks to said float, a pivoted mast on said planks, means connecting said float to a vessel and means to swing said mast into a vertical position when the vessel sinks relatively to 40 said float.

2. A mark buoy comprising in combination a ring float, two planks arranged parallel to each other on one side of said float, means to connect said planks to said float, hinges 50 at one end of said planks, means to connect a pivoted mast to said hinges and between said planks and a counterweight on said mast to swing it into vertical position when the vessel sinks relatively to said float. 55

In witness whereof, I have hereunto signed my name this 9th day of July 1919, in the presence of two subscribing witnesses,

MAURICE VITRAC.

Witnesses:

ANTOIN MONTEILHET,
CHAS. P. PRESSLY.
